[57] CLAIM

The ornamental design for a motorcycle side pannier, as
shown.

DESCRIPTION

FIG. 1 is a top perspective view of a motorcycle side
pannier showing my new design;

FIG. 2 is a bottom plan view thereof;

FIG. 3 is an elevational view of the side opposite to that
shown in FIG. 1; and

FIG. 4 is an elevational view of the end opposite to that
shown in FIG. 1.

FIG.1.

FIG.2.

FIG.3.

FIG.4.
